UNITED STATES PATENT OFFICE.

ROBERT DEMING, OF CINCINNATI, OHIO.

WELL PUMP.

Application filed October 26, 1927. Serial No. 228,768.

This invention relates to pumping means for drilled wells and more particularly to pumps for oil and gas wells in which gas under pressure is utilized to discharge the liquid from the well.

Quite frequently, it happens that oil or gas wells pass through a plurality of liquid or liquid and gas bearing strata, and it has heretofore been the practice either to pump 10 the liquid from a plurality of strata through a single conduit or to block the flow to the casing from all but one of the strata.

The present invention has for its object to provide a means by which liquid or gas 15 or liquid and gas can be separately drawn from strata at different levels and at different pressures, thus avoiding a mixture of the liquids and gases flowing from the different strata and permitting the liquid 20 or gas or liquid and gas to be taken independently from each stratum at the rate which it naturally flows therefrom, thereby very materially increasing the production of the well and maintaining higher gas pressures where the pressure from one stratum 25 might otherwise be fed back into a stratum of lower pressure and the ultimate pressure thus objectionably reduced with the loss of considerable gas.

30 A further object is to provide pumping means of the character above described which is of simple and practical construction and which can be readily assembled in the bore of the well.

35 The following description and accompanying drawings set forth in detail certain means embodying the invention, the disclosed means, however, constituting but one of the various mechanical forms in which 40 the principle of the invention may be employed.

Reference should be had to the accompanying drawings forming a part of this specification in which Fig. 1 is a diagrammatic sectional view showing a well to which the pumping means of the present invention is applied, the connections at the top of the well not being shown in this figure.

50 Fig. 2 is an enlarged section of the well similar to Fig. 1 but showing the well casing in vertical section.

Fig. 3 is a vertical section through the upper portion of the pump casings showing

the connections with the liquid conducting 55 pipes and the gas outlet pipes for the well constructions shown in Figs. 1 and 2; and

Fig. 4 is a corresponding view of the upper end of the pump casing showing special connections for use in a particular type of 60 well.

Figs. 1 and 2 of the drawing show a drilled well having bore 1 extending through the upper and lower strata 2 and 3 from which there is a flow of liquid or liquid 65 and gas. Within the bore 1, there is an outer casing 4 of conventional character which fits within the bore of the well and extends downwardly therein past the upper stratum 2. This casing may embody several 70 sections of different diameter as will be apparent to those skilled in the art. The upper end of the casing 4 is closed by a cap 5 and within this casing there is an inner tubular casing 6 which is of a diameter considerably less than that of the outer casing. The inner casing or well tubing 6 in the illustrated application of the invention, extends to the lowermost pay stratum substantially at the bottom of the well and some 75 distance below the upper stratum 2. The lower end portions of the casing 6 has a packer 7 disposed above the pay stratum 3 which seals the space between the inner casing 80 and the sides of the well so that liquid or gas issuing from overlying portions of the well or from the underlying stratum cannot pass to stratum 3 and so that independent connection is established by casing 85 6 with stratum 3. Casing 6 also has a second 90 packer 8 arranged somewhat below stratum 2. This packer provides a seal between casing 4 and tubing 6. The packer 8 and the casing 6 substantially provide a seal in the well casing 4 below the pay stratum 2 and 95 seal the overlying portions of the well from the underlying portions so that liquid and gas from one portion of the well do not interfere with the operation of other portions.

The portion of the outer casing 4 passing 100 through the pay stratum 2 is perforated by a large number of openings 9 formed in the side wall of the casing through which liquid or liquid and gas from stratum 2 may flow to the interior of the outer casing. The lower end portion of the tubing 6 that passes through the lower stratum 3 is provided with similar openings 10 through 105

which liquid or liquid and gas from stratum 3 may flow to the interior of the inner casing 6.

The well casing 4 also has a suitable packer 5 11 positioned below stratum 2 and another packer 12 positioned above stratum 2 with the perforated portion of the casing disposed therebetween. This arrangement seals the well casing 4 from cavings and from water 10 above and below the pay stratum 2 and provides for the admission to the casing 4 of gas or gas and liquid from stratum 2 through the casing perforations 9.

Cap 5, which closes the upper end of the 15 outer casing 4 is provided with an opening in which is secured a short vertical pipe 13, which carries a gland at its upper end through which the inner casing 6 extends, the gland forming a fluid tight seal around 20 the exterior of the casing 6, so that gas cannot escape along the surface of the casing 6. To the upper end of the casing 6, there is attached a fitting 15 which has a lateral extension 16 to which is attached a gas outlet 25 pipe 17 and through which extends a liquid conducting pipe 19, the fitting 15 is relatively small in cross sectional area as compared to the cross sectional area of the casing 6, the pipe 19 extending from the upper end of the 30 casing to adjacent the lower end thereof at the bottom of the well.

Cap 5 at the upper end of the casing 4 is provided with a second opening in which is secured a short pipe 20 which has fitting 35 21 at its upper end provided with a lateral extension 22 to which is attached a gas outlet pipe 23. At its upper end, the fitting 21 is provided with a gland 24 through which extends a liquid conducting pipe 25, which 40 passes through the fitting 21 and pipe 20 into the casing 4 exteriorly of the casing 6. The pipe 25 extends from the upper end of the casing to a point adjacent the packer 8 of the inner casing preferably below the 45 upper stratum 2.

The well tubing or inner casing 6, which is closed at its upper end except for the outlet 17 and at its lower end except for its 50 openings 10, provides a chamber extending from adjacent the ground level to the lower stratum 3 so that the liquid and gas from the stratum 3 may be extracted independently through the casing 6.

The space surrounding the tubing 6 above the packer 8 thereof is closed except for the 55 gas outlet 23 at the upper end and the openings 9 through which the liquid and gas may flow from the stratum 2 into the interior of the casing 4, thus providing a second chamber extending from adjacent the ground level to the upper stratum 2, through which liquids or liquids and gases may be extracted from the stratum 2 independently of the liquids or liquids and gases from the stratum 3.

65 The liquid pumping means of the present

invention is preferably the same as that disclosed in my co-pending application, Serial No. 198,496, filed June 13, 1927, patented Jan. 8, 1929, #1,697,856, in which there is disclosed means for utilizing the pressure of natural gases flowing together with liquid into the well casing for pumping the liquid out of the well. The pipe 19 is provided at intervals along its length with small apertures 26 in the wall thereof for admitting 70 gas in fine streams to the interior of the pipe to provide a continuously moving stream of gas and dispersed particles of finely divided liquid having the characteristics of a gas. As more fully explained in the above mentioned application, these small apertures are so positioned along the length of the pipe that they serve to maintain the liquid in a state of extremely fine subdivision, so that they will be carried along with the current 80 of gas whereby relatively small gas pressure is required to elevate the liquid. Flow of gas through the outlet pipe 17 may be controlled by a valve 28 and the flow of gas with liquid particles in suspension through the 85 pipe 19 may be controlled by a valve 29. If sufficient pressure is generated in the casing 6 by the gases issuing from the stratum 3, this pressure may be regulated by adjusting the valve 28 to regulate the escape of gas 90 and by adjusting the valve 29 to regulate the pressure in the pipe 19. The pressures in the pipe 19 and within the casing 6 around the pipe 19 are preferably so adjusted that the liquid is discharged through 95 the pipe 19 at substantially the rate at which it flows from the stratum 3. If the pressure generated by gases issuing from the stratum 3 is insufficient to elevate the liquid 100 at the desired rate, the necessary difference in pressure between the interior pipe 19 and the space surrounding the pipe within the casing 6 may be produced either by applying suction to the pipe 19 to reduce the pressure therein or by introducing gas under pressure 105 into the casing 6 through the pipe 17. The liquid is pumped from the chamber formed within the outer casing 4 exteriorly of the casing 6 above the packer 8 thereof in exactly the same manner as from the 110 lower portion of the casing 6, the pipe 25 being provided with small spaced openings 115 27 along the length thereof, corresponding to the openings 26 in the pipe 19, so that gas pressure in the outer chamber exteriorly of the pipe 25 serves to dispense the liquid particles in the gas stream and to thus carry the liquid in a finely divided state through the pipe 25. The gas outlet pipe 23 is preferably provided with a valve 30 by which the pressure within the outer casing may be 120 regulated and the pipe 25 is preferably provided with a valve 31 by means of which the pressure within the pipe 25 may be regulated. As in pumping the liquids from the 125 130

bottom of the well, the pressures are so regulated that the liquid is pumped from the outer chamber at substantially the rate at which it flows into the chamber from the 5 stratum 2.

The invention is obviously applicable to wells of widely different characteristics. For instance, if the upper stratum produces liquid with very little gas, the liquid could 10 be satisfactorily removed by connecting the pipe 23 into the line 17, as shown in Fig. 4. This connection is made by pipe 34, valve 35 and fitting 36. The pressure of gas fed into casing 4 through line 23 is regulated by 15 the valve 35, the valve 30 remaining closed. In this way gas pressure from one stratum is used to elevate liquid from another stratum and only such pressure as is necessary to elevate the liquid from stratum 2 is used. 20 It will be apparent that the present invention provides a means for simultaneously pumping liquids from strata at different levels through the single well bore and for positively preventing unintentional mixture 25 of the liquids and gases flowing from the different strata. Furthermore, it will be apparent that this invention provides a pumping means by which the maximum flow of liquids or gases or liquids and gases may be 30 obtained from each of the strata tapped by the well, thereby obtaining a maximum production of liquids and of gases.

What I claim is:

1. In a pump for a well having a bore 35 which intersects a plurality of liquid bearing strata, casing members within the bore subdividing the same into separate chambers, each extending downwardly from adjacent the ground level and each having means 40 for admitting liquid thereto from one of the liquid bearing strata, and means for pumping liquid from each of said chambers.

2. In a pump for a well having a bore which intersects a plurality of liquid bearing strata, casing members within the bore 45 subdividing the same into separate chambers, each extending downwardly from adjacent the ground level and each having means for admitting liquid thereto from one of the liquid bearing strata, and means for independently conducting liquid and gas from 50 each of said chambers.

3. In a pump for a well having a bore which intersects a plurality of liquid bearing strata, casing members within the bore 55 subdividing the same into separate pressure chambers, each extending downwardly from adjacent the ground level and each having openings through which liquid may be admitted from one of the liquid bearing strata, and a pipe for conveying the liquid from 60 each of said chambers, each pipe extending into the upper end portion of one of the chambers and downwardly therein, each pipe being of a cross sectional area relatively

small as compared to that of the pressure chamber into which it extends.

4. In a pump for a well having a bore which intersects a plurality of liquid bearing strata, casing members within the bore 70 subdividing the same into separate pressure chambers, each extending downwardly from adjacent the ground level and each having openings through which liquid may be admitted from one of the liquid bearing strata, 75 and a pipe connected to the upper end of each pressure chamber for discharging gas from the chamber or admitting gas under pressure thereto.

5. In a pump for a well having a bore 80 which intersects a plurality of liquid bearing strata, tubular casing members positioned one within another in the bore, said casing members being of different diameters and providing a plurality of chambers 85 extending downwardly from adjacent the ground level, means for closing the upper ends of each of said chambers, means carried by an inner casing member for sealing the lower end of the chamber surrounding the 90 same below one of said liquid bearing strata, means for admitting liquid to each chamber from one of the liquid bearing strata, and means associated with each chamber for pumping liquid therefrom. 95

6. In a pump for a well having a bore which intersects a plurality of liquid bearing strata, tubular casing members positioned one within another in the bore, said casing members being of different diameters 100 and providing a plurality of chambers extending downwardly from adjacent the ground level, means for closing the upper ends of each of said chambers, means carried by an inner casing member for sealing the lower end of the chamber surrounding the 105 same below one of said liquid bearing strata, means for admitting liquid to each chamber from one of the liquid bearing strata, and a pipe extending into the upper 110 end of each chamber to adjacent the bottom thereof for conducting liquid from the chamber, each pipe being relatively small in cross section as compared to the cross sectional area of its chamber. 115

7. In a pump for a drilled well, the bore of which intersects a plurality of liquid bearing strata, an outer tubular casing fitting within the bore, an inner tubular casing of a diameter considerably smaller than the first which extends to adjacent the lowermost liquid bearing stratum, means for closing the upper end of the inner casing member, means at the upper end of the outer casing members for closing the space between the casing members, means carried by the inner casing member for sealing the space surrounding the same below the uppermost liquid bearing stratum, and independent means for pumping liquid from 120 125 130

upper and lower strata including a pipe within the inner casing member and extending to adjacent the bottom of the well and a pipe in the space between the inner and outer casing members and extending from the upper end thereof to adjacent said sealing means.

8. A well having a bore which intersects a plurality of liquid bearing strata, and casing members within the bore subdividing the same into separate chambers, each extending downwardly from adjacent the ground level and each having means for admitting fluids thereto from one of the strata, and means for independently removing fluids from each of said chambers.

9. A well having a bore which intersects a plurality of liquid bearing strata, casing

members within the bore subdividing the same into separate chambers, each extending downwardly from adjacent the ground level and each having means for admitting fluids thereto from one of the strata, and means for independently pumping liquid from each of the chambers.

10. A well having a bore which intersects a plurality of liquid bearing strata, means utilizing gas pressure from one stratum to remove liquid from the other stratum, and casing members within the bore subdividing the same into separate chambers, each extending downwardly from adjacent the ground level and each having means for admitting fluids thereto from one of the strata.

In testimony whereof I affix my signature.

Acting Commissioner of Patents.

upper and lower strata including a pipe within the inner casing member and extending to adjacent the bottom of the well and a pipe in the space between the inner and outer casing members and extending from the upper end thereof to adjacent said sealing means.

8. A well having a bore which intersects a plurality of liquid bearing strata, and casing members within the bore subdividing the same into separate chambers, each extending downwardly from adjacent the ground level and each having means for admitting fluids thereto from one of the strata, and means for independently removing fluids from each of said chambers.

9. A well having a bore which intersects a plurality of liquid bearing strata, casing

members within the bore subdividing the same into separate chambers, each extending downwardly from adjacent the ground level and each having means for admitting fluids thereto from one of the strata, and means for independently pumping liquid from each of the chambers.

10. A well having a bore which intersects a plurality of liquid bearing strata, means utilizing gas pressure from one stratum to remove liquid from the other stratum, and casing members within the bore subdividing the same into separate chambers, each extending downwardly from adjacent the ground level and each having means for admitting fluids thereto from one of the strata.

In testimony whereof I affix my signature.
